UNITED STATES PATENT OFFICE.

JAMES D. FOSTER, OF MONTGOMERY, ALABAMA.

OX-YOKE.

Specification of Letters Patent No. 22,637, dated January 18, 1859.

To all whom it may concern:

Be it known that I, JAMES D. FOSTER, of 5
Montgomery, in the county of Montgomery
and State of Alabama, have invented a new
and useful Improvement in Ox-Yokes; and
I do hereby declare that the following is a
full, clear, and exact description of the
same, reference being had to the annexed
drawings, making a part of this specification,
10 in which—

Figure 1, is a front view of my invention.
Fig. 2, is an end view of ditto.

Similar letters of reference indicate cor- 15
responding parts in the two figures.
The object of this invention is to facilitate
the adjustment of the yoke to the necks of
the animals and also to facilitate its de-
tachment therefrom.

The invention consists in forming each 20
bow of the yoke of four parts, the two upper
parts of each bow being permanently at-
tached to the stock and the two lower parts at-
tached to the upper parts by hinges or joints
so that the lower parts may be opened or 25
distended to be readily fitted and secured
on the necks of the animals or removed
therefrom.

To enable those skilled in the art to fully 30
understand and construct my invention I
will proceed to describe it.

A, represents the stock of the yoke, about 35
one half of it is shown in Fig. 1, and B, rep-
resents a bow which is fitted to the part of
the yoke shown in the drawings. The stock
A, is of the usual form and construction and
therefore does not require minute descrip- 40
tion. The bow B, is also of the usual form,
but its construction is widely different from
the ordinary kinds in general use. There
are of course two bows to each stock, but as
they are precisely similar, one only is 45
shown. The bows are of the usual form
and are attached to the stock at the same
points as those of the ordinary yokes. The
bows are formed each of four parts a, a, b, b'.
The two upper parts a, a, are firmly secured 50
in the stock A, and the two lower parts b, b',
are connected to the lower ends of the parts
a, a, by hinge joints c, having straps d, con-
nected to them which cover the whole or

nearly the whole of the outer edges of the
parts below the stock. The lower end of the
part b, has a dowel pin e, projecting from it
and the lower end of the opposite part b',
has a hole to receive the dowel pin when the 55
parts b, b', are closed.

The lower ends of the straps d, have the
fastening C, secured to them for locking the
parts b, b', together. This fastening is
formed by having a loop e', attached by an 60
eye f, to the strap of the part b', of the bow,
and to the lower end of the strap of the part
b, of the bow a curved rod g, is attached by
a joint. In order to secure the lower ends
of the parts b, b', together the rod g, is 65
passed through the loop e', and is bent or
turned over toward the strap to which it is
attached, the rod being kept in proper posi-
tion by a loop or eye h, which is fitted on a
rod i, attached to the part b', and passed 70
over the end of the rod g, as plainly shown
in Fig. 1. The fastening C, it will be seen
locks firmly the ends of the parts b, b', to-
gether, and the dowel pin e, prevents the
parts b, b', from rocking. 75

By referring to Fig. 1, it will be seen that
the joints c, which connect the parts b, b',
with the parts a, a, are some distance above
the lower ends of the parts a, a, as the up-
per ends of the parts b, b', are provided with 80
tenons which fit in the slots in the lower
ends of the parts a, a. It will be seen that
by loosening the fastenings C and distend-
ing the parts b, b', the bows may be fitted
on the necks of the animals and also de- 85
tached therefrom with the greatest facility.

Having thus described my invention what
I claim as new and desire to secure by Let-
ters Patent, is—

Constructing the bows B, of four parts 90
a, a, b, b', the parts a, a, being permanently
attached to the stock A, and the parts b, b',
attached by hinge joints c, c, to the parts
a, a, and provided with a fastening C, sub-
stantially as and for the purpose set forth. 95

JAMES D. FOSTER.
